Attorney

UNITED STATES PATENT OFFICE.

ROBERT E. LAUCK, OF KANSAS CITY, MISSOURI.

OIL BURNER.

Application filed November 6, 1924. Serial No. 748,167.

To all whom it may concern:

Be it known that I, ROBERT E. LAUCK, a citizen of the United States, residing at Kansas City, in the county of Jackson and 5 State of Missouri, have invented certain new and useful Improvements in Oil Burners, of which the following is a specification.

My invention relates to oil burners and one object is to provide a burner of this 10 character in which the fuel oil is vaporized and intimately intermixed with a maximum amount of air to obtain efficient combustion at a minimum expenditure of oil.

A further object is to provide a burner 15 consisting of but few parts which may be manufactured and assembled at small cost.

Another object is to form and arrange the parts in such manner that there will be 20 no small orifices, or restricted passageways to become clogged with carbon or other products of combustion.

In order that the invention may be fully understood, reference will now be had to the accompanying drawing, in which:

25 Fig. 1 is a side elevation partly in section of the burner.

Fig. 2 is a cross section on line II—II of Fig. 1.

30 Fig. 3 is a modified form of a portion of the burner.

Referring now more particularly to Figs. 1 and 2, 3 designates a retort which may be made in different forms to fit different shaped fire boxes in stoves, furnaces, etc. 35 Said retort consists, preferably, of one casting having a centrally-disposed neck 4 rising from a trough 6 near the base 8 of the retort. Fuel oil is supplied to the retort 3 through a pipe line 10, provided with 40 a suitable valve 12 whereby the flow of oil to the retort may be regulated as desired.

14 designates a deflector arranged at the upper end of the neck 4. Said deflector consists of a semispherical head 16 and ribs 45 18 which latter are integral with and support the former and in turn are provided with shoulders 20, which rest upon the upper end of the neck 4. The neck 4 and the ribs 18 form passageways 22 through which 50 the vaporized fuel escapes from the retort 3 into a primary mixing chamber 24.

The primary mixing chamber 24 is formed by a dome 26 provided with spacing lugs 28 which rest upon the head 16. As shown 55 by Fig. 1, the dome 26 encloses the head 16 and the upper portion of the neck 4

but is of greater diameter to leave the mixing chamber 24 into which the vaporized fuel flows from the retort 3 through the passageways 22. An air port 30 is formed 60 in the upper portion of the dome 26 for the admission of air to the mixing chamber 24 where it combines with the vaporized fuel and forms a rich combustible mixture.

32 designates a hood extending downwardly over the dome 26 and to within a short distance of the trough 6. Said hood 32 is held in concentric relation with the neck 4 and the dome 26 by spacing lugs 33, projecting from the retort 3. The hood 32 65 is of greater diameter than the dome 26 to form a supplemental mixing chamber 34, which is supplied with a relatively large volume of air through a primary air tube 36 communicating at one end with the upper portion of the hood 32 and at its opposite end with a suitable blower 38. Additional air is supplied to the primary tube 36 through a supplemental air tube 40, 70 which latter is connected to the former by suitable means such as a T-coupling 42.

In practice the burner 32 may be started by allowing oil to flow into the retort 3 and overflow into the trough 6 where it is 75 ignited. The flame thus produced heats the retort 3 and causes vaporization of the oil 80 therein. As the vapor escapes through the passageways 22 it initially combines with the air admitted to the primary mixing chamber 24 where it takes up more air supplied by the tube 36 and ignites as it passes 85 outwardly between the lower end of the hood 32 and trough 6. The continuous flame thus produced continues to heat the retort 3 and vaporizes the oil admitted 90 thereto and also heats the air flowing through the chambers 24 and 34, so that 95 there will be no danger of such air cooling and condensing the vapor. A large proportion of the flame also spreads against 100 the walls of the fire box in which the burner is arranged, thereby heating said fire box to a high degree.

By providing a large volume of air as 105 above pointed out an economical and efficient mixture is obtained and the air flowing through the port 30 sweeps away any carbon or other deposits which might otherwise lodge in and clog the chamber 24.

In the modified form disclosed by Fig. 3, 110 a cage-like deflector 14^a is substituted for the deflector 14. Said deflector 14^a has a

port 30^a in its upper portion for the admission of air which escapes through slots 50 in said upper portion, said slots 50 being separated from passageways 22^a in the lower portion of the deflector by a partition 52. The lower end of the deflector 14^a is reduced to fit into the upper end of the neck 4^a and has a shoulder 20^a whereby said deflector is supported upon said neck.

10 While I have shown two forms of the invention; I reserve the right to make such other changes in the construction, combination and arrangement of parts as properly fall within the spirit and scope of the invention as claimed.

Having thus described my invention, what I claim and desire to secure by Letters Patent, is:—

1. In a burner of the character described, a retort terminating at its upper end in a reduced neck, a deflector at the upper end of said neck, a dome extending over said deflector and provided with an air port, and a hood extending over said dome and provided with an air inlet.
2. In a burner of the character described, a retort terminating at its upper end in a reduced neck, a deflector at the upper end

of said neck consisting of a semispherical portion and ribs, which latter have shoulders resting on said neck, and a dome having an air port and a plurality of lugs which latter rest upon the deflector and support said dome.

3. A burner consisting of a retort terminating at its upper end in a reduced neck, a deflector at the upper end of said neck, a dome extending over said deflector and provided with an air port, a hood extending over said dome, and means for supplying said hood with air.

4. A burner consisting of a retort terminating at its upper end in a reduced neck, a deflector at the upper end of said neck, a dome extending over said deflector and provided with an air port, a hood extending over said dome, a primary air tube connected to said hood to supply the same with air, a blower connected to said primary air tube, and a supplemental air tube connected to the primary air tube between the discharge end of the tube and the blower.

In testimony whereof I affix my signature.

ROBERT E. LAUCK.
